UNITED STATES PATENT OFFICE.

JAMES HAY HUTCHISON, OF LONDON, ENGLAND.

DESIGN FOR A FONT OF PRINTING-TYPE.

SPECIFICATION forming part of Design No. 33,531, dated November 6, 1900.

Application filed September 22, 1900. Serial No. 30,857. Term of patent 14 years.

To all whom it may concern:

Be it known that I, JAMES HAY HUTCHISON, a subject of Her Majesty the Queen of Great Britain, and a resident of the city of London, 5 England, have invented and produced a certain new and original Design for a Font of Printing-Type, of which the following is a full, clear, and exact specification, reference being had to the accompanying drawing, forming a part hereof.

I have illustrated my invention in the accompanying drawing, in which I have shown a plan view of a complete set of type, upper and lower case.

5 The leading or material feature of my design consists of the form of characters which presents to the eye a new and attractive appearance; and my invention relates to the configuration or design of the type-faces, the same being the usual characters that go to make up a font of type.

All the letters are made up of curved lines and scrolls. The leftline of A and H and the upright line of B, F, I, J, K, P, and R and 15 the tail of G are scrolls ending in a bulb. The tops of A, H, I, J, K, L, M, N, U, V, and

W have scroll serifs. The two curves in B and E and the inclined lines in K are joined by an open loop. The upright line and the curved line of the D and the upright and lower line of L and Z are joined by an open loop at the bottom. The upper curves of B, D, P, and R terminate in bulbs. The top of T joins the curved upright by an open loop.

It will be noted that the font is in the nature of an italic script, and this characteristic appears not only in the upper-case, but also in the lower-case letters, which in shape, configuration, and ornamentation correspond in general with those of the upper-case.

Having described my invention, what I claim as new, and desire to secure by Letters Patent, is—

The design for a font of printing-type, substantially as described and shown.

Signed at Bouverie House, Salisbury square, in the city of London, England, this 4th day of September, 1900.

JAMES HAY HUTCHISON.
